US00D809514S

(12) **United States Design Patent** (10) Patent No.: **US D809,514 S**
Lee et al. (45) Date of Patent: ** Feb. 6, 2018

(54) **ELECTRONIC DEVICE**

- (71) Applicant: **Samsung Electronics Co., Ltd.**, Suwon-si (KR)
- (72) Inventors: **Minhyouk Lee**, Seongnam-si (KR); **Hyounghsin Park**, Seoul (KR); **Jooho Seo**, Seoul (KR)
- (73) Assignee: **SAMSUNG ELECTRONICS CO., LTD.**, Suwon-si (KR)

(**) Term: **15 Years**

(21) Appl. No.: **29/597,768**

(22) Filed: **Mar. 20, 2017**

Related U.S. Application Data

- (63) Continuation of application No. 29/539,064, filed on Sep. 10, 2015.

(30) **Foreign Application Priority Data**

Jul. 15, 2015 (KR) 30-2015-0035544

(51) LOC (11) Cl. **14-03**

(52) U.S. Cl.

USPC **D14/348**

(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines depict portions of the electronic device that form no part of the claimed design.

1 Claim, 6 Drawing Sheets
